UNITED STATES PATENT OFFICE.

JOHN W. CLARK, OF PROVIDENCE, RHODE ISLAND.

RAIL JOINT.

Application filed March 13, 1925. Serial No. 15,320.

To all whom it may concern:

Be it known that I, JOHN W. CLARK, a citizen of the United States, residing at Providence, in the county of Providence and 5 State of Rhode Island, have invented certain new and useful Improvements in Rail Joints, of which the following is a specification.

This invention relates to an improved rail joint wherein a supporting member is positioned beneath the meeting rail ends and is supported entirely by the joint structure in such a manner that the supporting member is continually held in contact with the bases of the rails.

15 One object of the invention is to provide a structure of the character described wherein the supporting member is in turn supported directly from the inclined outer base portions of the fish plates, and any tightening 20 of the clamping means provided for taking up wear on the fish plates, will result in positively forcing said supporting member directly upwardly against the bases of the meeting rail ends thereby clamping the supporting member firmly against the bases of the rails and gripping the rail ends, as it were, between the jaws of a vise to hold each 25 of the rail ends against movement independently of the other.

30 Another object of the invention is to provide a structure of this character wherein the pivot points of the side members are so arranged and the parts so proportioned that the lines of force developed in clamping the 35 structure intersect at a point at or adjacent to the longitudinal center lines of the rail bases to thereby most effectively force the supporting member into contact with the bases of the meeting rail ends and continually 40 hold the supporting member in contact therewith.

A further object of the invention is to so proportion the side members and locate their pivot points that the parts of said 45 side members contacting with the outer surfaces of the fish plates will properly contact with the outer surfaces of said fish plates in different positions of said fish plates as they are forced inwardly towards the rails to 50 take up wear thereon.

Another object of the invention is to provide a structure of the character described wherein the fish plates are engaged by a plurality of contacts on the side members 55 which are adapted to furnish a direct sup-

port for the heads of the meeting rail ends, the parts being so proportioned that the several contacts will engage the fish plates in a plurality of adjusted positions of the fish plates whereby the wear upon the fish 60 plates may be taken up from time to time while constantly maintaining a line of support between the rail heads and the bases thereof.

Other objects and advantages of the invention relate to certain improved details of construction and novel methods of operation, as will be more fully set forth in the detailed description to follow.

Referring to the accompanying drawings 70 and forming a part of this specification:—

Fig. 1 is a side elevational view of my improved rail joint;

Fig. 2 is a vertical sectional view, taken along the line 2—2 of Fig. 1;

Fig. 3 is a vertical sectional view of a modified form of the structure, and,

Fig. 4 is a diagrammatic view illustrating the positions of the bearing points of the side members in varying adjusted positions 80 of the fish plates.

In the accompanying drawings 1 and 2 designate the meeting rail ends each of which is provided with a head portion 3, a web portion 4 and a base 5, which may be 85 supported by ties 6 of the conventional type. Fish plates 7 and 8 of similar construction are positioned upon opposite sides of the web portions 4 of the meeting rail ends, each of said fish plates being provided with an 90 inwardly and downwardly inclined shoulder 9 adapted to bear against the under surface of the rail heads, and an inwardly and upwardly inclined shoulder 10 adapted to bear against the upper surface of the rail base 95 portions. The outer surface of each fish plate is made up of a head and base flanges 11 and 12 and a substantially straight vertical portion 14 located between the head and base flanges.

100 The joint structure comprises a supporting member 16 having spaced ears 17 extending somewhat beyond the longitudinal side edge of the rail base and upwardly inclined as shown in Fig. 2. The spaced ears 17 located upon each side of the supporting member are provided with aligned openings 18 for the reception of a pin 19, which passes through a similar opening 20 in that portion of one of the side members 21 which is 110

positioned between the spaced ears 17 upon one side of the supporting member. The outer edge portions of the supporting member are cut away as indicated by reference character 22, and the edges thus cut away are inclined downwardly and inwardly as shown at 23, these inclined portions being provided with curved bearing surfaces 24 for a purpose which will be more fully described hereinafter.

The side members 21 are of similar construction, each being of angular cross-section as seen in Fig. 2 and having the opening 20 for the reception of the pin 19 located at or adjacent to the vertex of the angle formed. The upwardly extending portion 26 of each side member 21 makes an angle of substantially 45 degrees with the downwardly extending portion 27 thereof where-by the downwardly extending portion 27 of the side member extends in a direction substantially parallel to the inclined surface 23 of the supporting member and upon pressure being exerted therebetween the upwardly extending portion 26 of the side member will be forced into binding contact with the curved outer surfaces at the base of the fish plate to positively draw the supporting member 16 directly upwardly and force the same against the base of the rail ends.

While in the present instance the angle which the upwardly extending portion 26 of each side member 21 makes with the downwardly extending portion 27 thereof is approximately 90 degrees it is to be understood that the angle of inclination of the parts 26 and 27 relative to each other may be either greater or less than 90 degrees depending upon the proportions given to other parts of the structure and the location of the points of pivotal connection of the side members with the supporting member. A jack-screw 28 is threaded in the downwardly extending portion 27 of each side member and arranged to bear against the curved bearing surface 24 for exerting pressure between the downwardly extending portion 27 of each side member and the inclined edge 23 of the supporting member to force the upwardly extending portion 26 of each side member into gripping engagement with the fish plates and clamp the supporting member 16 and rail bases 5 between the upwardly extending portions 26 of the side members which engage the curved surfaces at the bases of the fish plates and the ends of the jack-screws 28 whereby the supporting member 16 and rail bases 5 are clamped together as between the jaws of a vise, the lines of force exerted by the upwardly extending portions 26 engaging the outer curved surfaces at the base of the fish plates and the lines of force exerted by the jack-screws 28 substantially intersecting in a vertical plane located approximately at the longitudinal

centers of the rails. This clamping action of the parts tends to positively force the supporting member 16 directly upwardly against the longitudinal centers of the rail ends, the directions of the several forces being such as to concentrate the effect of the force exerted, along the longitudinal center lines of the rails.

The upwardly extending portions 26 of the side members have each three points of bearing where they contact with the fish plates as may be seen upon reference to Fig. 2 of the drawings:—the point 30 where the extreme end of the upwardly extending portion of the side member contacts with the head 11 of the fish plate, the point 31 where a portion of the upwardly extending portion of the side member contacts with the vertical portion 14 of the fish plate, and the point 32 where the lower rounded portion of the upwardly extending portion 26 of the side member contacts with the outer curved portion of the base of the fish plate. The parts are so proportioned that the three points of contact above described will be effective after the fish plates have become worn and are consequently drawn closer towards each other, within such limits as constitute the probable maximum movements of the fish plates, as is diagrammatically illustrated in Fig. 4 of the drawings. In Fig. 4 of the drawings, the solid line designated by reference character 34 illustrates the initial position of the fish plate, while the dotted line 35 designates the position of the fish plate after the maximum degree of wear has taken place and the fish plate has been forced over towards the rail to compensate for the wear, 36 designates the pivot point of the side member and 37 the bearing point of the side member against the shoulder 11 of the fish plate in its original position, while 38 and 38' designates respectively, a point on the side member when in its original position and after the side member has been turned through the angle α . 40 designates the bearing point of the side member against the vertical portion 14 of the fish plate in its original position, while 40' designates the point on the side member bearing against the vertical portion 14 of the fish plate after the side member has been turned through the angle b . 41 designates the bearing point of the side member against the outer curved base portion of the fish plate when the fish plate is in its original position while 42 and 42' designates respectively a point on the side member when in its original position and after the side member has been turned through the angle c . The angles α , b and c are equal. The bearing points or contacts 38', 40' and 42' illustrate the new points of contact which the upwardly extending portion of the side member makes with the fish plate after the fish plate has been drawn

into closer engagement with the rail ends, the upwardly extending portion of the side member being so proportioned that as the side member is swung about its axis 36 and 5 raised slightly parts of the face of said side member will travel forward to contact with the fish plate and all of these contact points will uniformly engage the fish plate in its adjusted position indicated by the line 10 35. For positions of the fish plate intermediate the lines 34 and 35, other points on the upwardly extending portion of the side member will travel forward to engage the fish plates at the three points indicated.

15 While the diagrammatic representation as shown in Fig. 4 illustrates the principle involved and shows how the three point contact of the upwardly extending portion of the side member with the fish plate is maintained in various adjusted positions of the 20 fish plate, this showing is not entirely accurate for the reason that another factor enters into the adjustment which cannot be readily shown, as follows: As the fish plates 25 become worn, wear also takes place on the upper face of the supporting member 16 and on the bases of the rails, although to a less degree than on the fish plates, and, as a result of this condition the supporting member 30 is drawn upward slightly in tensioning the parts, which causes the pivot point 36 to be raised slightly in the new position of the parts. The elevation of the supporting member above the position which it initially occupies is very slight and for that reason cannot be readily illustrated but it is sufficient to raise the contact point 38 into engagement with the flange 11 of the fish plate as at 38' and to raise the point 40' slightly above the 40 level it would occupy if the pivot point remained fixed at 36. It also tends to bring a new point 42 on the curved contact surface 32 into engagement with the curved outer surface of the base of the fish plate at 42'. 45 The shape or contour of the several contacting surfaces carried by the upwardly extending portion 26 of each side member which bear against the fish plates at the various points of contact are such that when moved inwardly and as the pivot point 36 rises slightly these or similar points continue to engage the fish plate in such a manner as to maintain the fish plate in its original upright position in all of the various adjusted positions which the fish plate may assume.

50 Thus there is provided a three-point bearing of the upwardly extending portion of the side member against the fish plate in the various adjusted positions of the fish plate, whereby a plurality of contacts uniformly engage and properly support the fish plate in its various adjusted positions. It is, of course, understood that the above description applies equally to the fish plates and up-

wardly extending portions of the side members located on opposite sides of the rail ends.

55 Bolts 45 are passed through enlarged openings 46 formed in the upwardly extending portions 26 of the side members as well as through the fish plates 7 and 8 and rail web 4 to assist in drawing the upwardly extending portions of the side members into close engagement with the fish plates and 60 firmly connect the several parts. The enlarged openings 46 in the upwardly extending portions of the side members permit the necessary angular movement of the side members about their pivots to adjust the 65 same to compensate for wear on the fish plates and side members.

70 The heads of the bolts 46 may be rounded as indicated at 48 to suitably bear against the side of the upwardly extending portion 75 26 of the side member in all positions of the same and the nuts 49 may be similarly rounded as indicated at 50 to similarly bear against the upwardly extending portion 26 of the oppositely positioned side member, 80 whereby a proper bearing of the bolt heads and nuts is obtainable at all times. Bolts 52 are passed through the fish plates 7 and 8 and rail webs 4 adjacent the ends of the fish plates to additionally support the plates in 85 proper operative position.

90 The structure shown in Fig. 3 of the drawings is similar in all respects to that above described and shown in Fig. 2 thereof and similar reference characters have been applied thereto, except that the supporting member 60 is provided with a central upstanding portion 61 bearing directly against the longitudinal center line of the rail bases, while recesses 62 are formed in the supporting member on opposite sides of the upstanding portion 61 to provide a supporting member of less weight but so formed as to be constantly drawn into contact with the longitudinal center lines of the rail bases by 100 means of the clamping action exerted by the jack-screws 28 and the bearings of the upwardly extending portions 26 of the side members on the outer curved surfaces at the 105 bases of the fish plates.

110 While it is my purpose to employ fish plates upon opposite sides of the meeting rail ends in order to strengthen the structure and additionally support the rail ends as well as serve to provide a direct support between the heads and bases of the rails, it is to be understood that under certain conditions it may be found practicable to eliminate the fish plates, in which case the upwardly 115 extending portions of the side members may be made of more substantial size and so formed as to fit between the heads and bases of the meeting rail ends on opposite sides thereof whereby the upwardly extending portions of the side members will serve as 120 125 130

effective substitutes for the fish plates and provide a support between the heads and bases of the rails as well as serve to draw the supporting member 16 against the bases 5 of the rails.

From the above description it will be seen that the structure above described provides a gripping clamp for directly and positively forcing the supporting member against the 10 longitudinal center line of the bases of the rail ends, the structure being so arranged that the supporting member is carried entirely by the rails and forced against the bases of the rails by force exerted downwardly and inwardly from the curved outer base portions of the fish plates, whereby the structure becomes in effect an integral portion of the rail. The provision of a plurality of contacts on the upwardly extending 15 portions of the side members insures proper and firm engagement of the upwardly extending portions of the side members with the fish plates and maintains the fish plates in proper vertical positions, in the various 20 adjusted positions of the latter.

The contact between the parts of the upwardly extending portion of each side member and the shoulder 11 of each fish plate together with the contact of the lower 30 portion of the upwardly extending portion of each side member and the outer curved base portion of each fish plate results in the formation of substantially vertical planes of support between the head and base portions of the rail ends and opposite the webs thereof, whereby independent movement 35 of the rail ends is reduced to a minimum and a support provided for those parts of the structure where such support is most 40 required.

Although I have shown and described the upwardly extending portions 26 of the side members as so formed as to provide three points of contact with the fish plates as at 45 30, 31 and 32, I may when desired so form the upwardly extending portions 26 of the side members as to eliminate one of the contacts, as for example, each upwardly extending portion may be so formed as to contact 50 with the fish plate only at the points 30 and 32 which will, in some cases, give sufficient support to the fish plate to maintain the same in its upright position and provide a line of support for the head 11 of the fish plate between the head and base thereof.

If desired the upwardly extending portions 26 may be formed to contact with the fish plates only at the points 31 and 32, or the portions 26 may be so formed as to make 60 extended contact with the vertical portions 14 of the fish plates.

Although I have shown and described a preferred form of my invention, it is to be understood that many changes may be made 65 in the details of construction as shown with-

out departing from the spirit and scope of my invention as set forth in the appended claims.

What I claim is:—

1. In a rail joint for meeting rail ends, 70 a pair of fish plates engaging the opposite sides of the meeting rail ends, a supporting member underlying the said meeting rail ends, side members pivoted to said supporting member and having portions engaging the fish plates adjacent to the bases thereof, and means for exerting pressure between said supporting member and the side members to grip the rail base between the fish plates and the supporting member. 75 80

2. In a rail joint for meeting rail ends, a pair of fish plates engaging the opposite sides of the meeting rail ends, a supporting member underlying said meeting rail ends, means carried by the supporting member 85 and engaging the bases of said fish plates for suspending the supporting member from the bases of the fish plates, and means for positively forcing said supporting member into binding engagement with the bases 90 of said meeting rail ends.

3. In a rail joint for meeting rail ends, a pair of fish plates engaging the opposite sides of the meeting rail ends, a supporting member underlying said meeting rail ends, 95 side members carried by said supporting member and overlying the bases of said fish plates, and means for exerting pressure between the overlying portions of said side members and said fish plates along lines intersecting at a point adjacent to the longitudinal center line of the rails whereby the said supporting member is positively forced into clamping engagement with the bases of 100 said rails. 105

4. In a rail joint for meeting rail ends, a supporting member underlying said meeting rail ends, side members pivotally connected to said supporting member and having portions projecting inwardly and overlying the bases of said meeting rail ends, and means 110 cooperating with said supporting member and said side members for clamping the bases of said meeting rail ends between said supporting member and the overlying portions of said side members. 115

5. In a rail joint for meeting rail ends, a supporting member provided with downwardly inclined faces and outwardly projecting portions, angular side members pivoted to the outwardly projecting portions of said supporting member and each having a portion extending downwardly in substantial parallelism with one of the inclined faces of the supporting member and a portion overlying the bases of said meeting rail ends, and means cooperating with the downwardly extending portions of said side members and the inclined faces of said supporting member to exert tension upon the 120 125 130

overlying portions of said side members and thereby clamp the bases of the meeting rail ends between the overlying portions of said side members and said supporting member.

5 6. In a rail joint for meeting rail ends, a pair of fish plates overlying the meeting ends of said rails, a supporting member underlying said rail ends, side members pivoted to said supporting member and provided with upwardly extending portions 10 engaging the said fish plates and shaped to provide a plurality of contacts, and means for drawing the upwardly extending portions of said side members into clamping engagement with said fish plates whereby the upwardly extending portions of said side members will contact with the fish plates substantially uniformly as the fish plates are drawn towards each other into 15 various adjusted positions to compensate for wear thereon.

20 7. In a rail joint for meeting rail ends, a pair of fish plates overlying the meeting rail ends, a supporting member underlying said rail ends, side members pivoted to said supporting member and provided with upwardly extending portions engaging said fish plates at a plurality of points and means for drawing the upwardly extending portions 25 of said side members into clamping engagement with said fish plates, the upwardly extending portions of said side members being so proportioned to provide contacts with said fish plates at the points 30 of engagement therewith whereby substantially uniform contact is maintained with said fish plates in various adjusted positions of said fish plates.

35 8. In a rail joint for meeting rail ends, a pair of fish plates overlying the meeting rail ends and each shaped to engage the lower surface of the rail head and the upper surface of the rail base, a supporting member underlying said meeting rail ends, side members pivoted to said supporting member upon opposite sides of said rail ends and each provided with an upwardly extending portion having a three-point contact with 40 one of the fish plates, and means for forcing the upwardly extending portions of said side members into clamping engagement with said fish plates.

45 9. In a rail joint for meeting rail ends, a pair of fish plates overlying the meeting rail ends and each shaped to engage the lower surface of the rail head and the upper surface of the rail base, a supporting member underlying said rail ends, side members pivoted to said supporting member upon opposite sides of said rail ends and each provided with an upwardly extending portion 50 adapted to engage each fish plate at points adjacent to the head and base thereof, whereby a line of support is provided 55 by the upwardly extending portion of said

side member to supplement the support afforded for the rail head by the fish plate, and means for drawing the upwardly extending portions of said side members into clamping engagement with said fish plates. 70

10. In a rail joint for meeting rail ends, a pair of fish plates overlying the meeting rail ends, a supporting member underlying the meeting rail ends, side members carried by said supporting member upon opposite sides of the meeting rail ends and each provided with an upwardly extending portion having a three line contact with one of the fish plates, and means for forcing the upwardly extending portions of said side members 75 into clamping engagement with said fish plates. 80

11. In a rail joint for meeting rail ends, a pair of fish plates overlying the meeting rail ends, a supporting member underlying the meeting rail ends and provided with inclined side edges, side members pivoted to said supporting member upon opposite sides of the meeting rail ends and having downwardly and inwardly extending portions 90 located adjacent to the inclined side edges of the supporting member and upwardly and inwardly inclined portions adapted to engage the fish plates, and means carried by the downwardly and inwardly inclined portions 95 of the side members engageable with the inclined side edges of the supporting member for forcing the upwardly and inwardly inclined portions of the side members into clamping engagement with the 100 fish plates.

12. In a rail joint for meeting rail ends, a pair of fish plates overlying the opposite sides of the meeting rail ends, a supporting member underlying the meeting rail ends, 105 side members pivoted to said supporting member upon opposite sides of the meeting rail ends, the pivot points of said side members being located above the bases of the meeting rail ends, and means for forcing the upwardly extending portions of said side members into clamping engagement 110 with said fish plates.

13. In a rail joint for meeting rail ends, a pair of fish plates overlying the opposite sides of the meeting rail ends, a supporting member underlying the meeting rail ends, and means carried by said supporting member and engaging the lower outer edges of 115 said fish plates whereby the supporting member is suspended from the lower curved outer surfaces of the fish plates. 120

14. In a rail joint for meeting rail ends, a pair of fish plates overlying the opposite sides of the meeting rail ends, a supporting member underlying the meeting rail ends, means carried by said supporting member and engaging the lower outer edges of the fish plates whereby the supporting member 125 is suspended from the lower curved outer 130

- surfaces of the fish plates, and means for maintaining the fish plates in upright position engaging the opposite sides of the meeting rail ends.
- 5 15. In a rail joint for meeting rail ends, a pair of fish plates overlying the meeting rail ends and each shaped to engage the lower surface of the rail head and the upper surface of the rail base, a supporting member underlying said rail ends and provided with inclined side edges, side members pivoted to said supporting member upon opposite sides of said rail ends and each provided with an upwardly extending portion adapted to engage each fish plate at points adjacent to the head and base thereof whereby a line of support is provided

by the upwardly extending portion of each side member to supplement the support afforded for the rail head by the fish plate, and a downwardly and inwardly inclined portion located adjacent to one of the inclined side edges of the supporting member, and means carried by the downwardly and inwardly inclined portions of the side members engageable with the inclined side edges of the supporting member for forcing the upwardly extending portions of the side members into clamping engagement with said fish plates.

In testimony whereof I have affixed my signature.

JOHN W. CLARK.
